UNITED STATES PATENT OFFICE

169,638

CURTAIN FABRIC

Max Sadinoff, New York, N. Y.

Application August 20, 1952, Serial No. 21,128

Term of patent 3½ years

(Cl. D47—6)

To all whom it may concern:

Be it known that I, Max Sadinoff, a citizen of the United States of America, residing in New York city, county of New York, and State of New York, have invented a new, original, and ornamental Design for a Curtain Fabric, of which the following is a specification, reference being had to the accompanying drawing, forming a part thereof.

In the drawing:

The figure is a plan view of a curtain fabric showing my new design.

The drawing shows a complete design unit which is repeated in regular succession along the length and width of the fabric.

I claim:

The ornamental design for a curtain fabric, as shown and described.

MAX SADINOFF.
